CLAIM

The ornamental design for a mass airflow housing support bracket, as shown and described.

DESCRIPTION

FIG. 1 is a front perspective view of the mass airflow housing support bracket.

FIG. 2 is a front view of the mass airflow housing support bracket.

FIG. 3 is a rear view of the mass airflow housing support bracket.

FIG. 4 is a left side view of the mass airflow housing support bracket.

FIG. 5 is a right side view of the mass airflow housing support bracket.

FIG. 6 is a top view of the mass airflow housing support bracket.

FIG. 7 is a bottom view of the mass airflow housing support bracket.

FIG. 8 is an isometric view of the mass airflow housing support bracket.

FIG. 9 is a right side exploded view of the mass airflow housing support bracket; and,

FIG. 10 is an isometric exploded view of the mass airflow housing support bracket.

The broken line showing of the mass airflow housing support bracket is for the purpose of illustrating environmental structure and forms no part of the claimed design.

1 Claim, 10 Drawing Sheets
